United States Patent Office

Des. 202,104
Patented Aug. 31, 1965

202,104

CHAIR

Merle C. Melchior, Los Angeles, Calif., assignor of one-half to Sidney Galper, Los Angeles, Calif.

Filed Sept. 29, 1964, Ser. No. 31,922

Term of patent 14 years

(Cl. D15—1)

I claim:

The ornamental design for a chair, substantially as shown.
